UNITED STATES PATENT OFFICE.

BERNARD FAY, OF PITTSBURG, PENNSYLVANIA.

BURGLAR-ALARM.

SPECIFICATION forming part of Letters Patent No. 285,023, dated September 18, 1883.

Application filed May 26, 1883. (Model.)

To all whom it may concern:

Be it known that I, BERNARD FAY, a citizen of the United States, residing at Pittsburgh, in the county of Allegheny and State of Pennsylvania, have invented certain new and useful Improvements in Bell-Pulls and Burglar-Alarms Combined, of which the following is a specification, reference being had therein to the accompanying drawings.

10 My invention relates to an improvement in bell-pulls and burglar-alarm combined; and it consists in an alteration of certain parts as described in Patent No. 206,899 of the United States, and in an addition of new parts, where-
15 by the bell-pull is made to work easier, and the alarm never fails to respond at a slight turn of the door-knob.

The bell-pulls now in use are objectionable, owing to the strength required to make them 20 ring, so that children or persons not having much strength can use them only by great efforts, and even then do not always succeed. Another objection is that after being used a short time they get out of order, owing to the 25 great strain on the wire that lifts the pivoted lever by which the hammer is made to strike the bell. The burglar-alarm combined with the mechanism of the bell-pull are objected to because they are weak and unreliable, owing to the yielding of the yoke on the knob- 30 handle that is connected by chains with the ringing apparatus. When the door-knob is turned slowly and with care, the ringing of the bell may easily be avoided.

35 My object has been to overcome these objections by connecting the bell-pull directly with the bell-striking mechanism, and by substituting for the lifting-wire cam a solid lever that is easily operated. I also adopt for the 40 burglar-alarm, in place of a yoke secured to the handle of the door-knob, a flat bar or plate through which passes the shank of the door-knob, so that it becomes impossible to turn the knob without causing the bell to 45 ring, as will be more fully described herein-after.

The accompanying drawings represent my invention.

Figure 1 is a rear elevation. Fig. 2 is a front elevation. Fig. 3 is a side view. Fig. 4 is a 50 rear elevation of the operating mechanism

with the bell removed. Fig. 5 is a detached view of the lever connected to the door-pull.

A represents a plate, of any suitable material and form, to be secured to the door or door-post. In this plate are two oblong openings, b and c, the one over the other, of which the upper one, b, is for the passage of a wire that connects the bell-pull B with the bell-striking mechanism, and the lower one, c, for a projection, f, on the rear side of the pull to pass through. The bell-pull B has on its rear side a projection, d, that serves as a check to hold the pull at a distance from the plate for the hand to seize it, and also for the attachment of a wire, e, that, after passing through the opening b, connects the pull directly with a lever, g, that causes the bell to strike when pulled. The other projection, f, on the rear side of the bell-pull B has a shoulder at its 65 lower edge, that, when the pull is drawn back to ring the bell, bears against the face of the plate A and prevents its being pulled farther than necessary. The projection f, after passing through the opening c, protrudes at the 70 rear of the plate A, and has its fulcrum in bearings formed behind and with the plate. At the end of the projection f is hooked a spiral spring, s, that, extending downward, has its lower end fastened to a pin projecting 75 from the rear of the lower end of the plate A. This spring, pulling downward, holds the bell-pull B closely against the outside of the plate when not forcibly drawn back, and restores it to its former position when set free. 85

The mechanism for striking the bell and the bell are on a plate, C, that is to be secured to the inside of the door or door-post opposite to the plate A. The connection between the bell-pull B and the mechanism is made by 90 means of a wire, e, attached to the projection d on the pull, and to the lever g, pivoted on the plate C under the bell. The lever g consists of a pivoted arm, from the side of which, near its end, projects a triangular cam, h, of 95 which the lower point reaches below the width of the arm of the lever x, so that when pulled down the slanting side, beginning at the point, is gradually brought to push back the lever x, that, in connection with other parts, causes the hammer to strike the bell. By the increased leverage of the cam, the pulling of the bell is 100

made much easier than heretofore, and not liable to become disarranged, as is the case when a wire is used for a similar purpose. In order to attach the door-knob to the same alarm as the door-pull, there is passed over the shank of the knob a lever, m , which projects equally at both ends beyond the shank. To each end of this lever m is attached a short chain, z^2 , which chains z^2 are fastened to one end of the triangular lever y . To the other end of this triangular lever y is secured the chain z , which extends upward and is fastened to the longer end of the lever x . To the shorter end of the lever x is attached the pivoted end piece, a^2 , which is beveled upon its inner edge, as shown. When the lever x is pulled downward, either by a direct pull on the chains attached to the door-knob, or is forced downward by a pull upon the lever g , having the projection h , the lever x forces the beveled end piece against the beveled end of the pivoted lever b^2 , and forces the lever b^2 to turn upon its pivot sufficiently to strike the alarm, when the lever b^2 is drawn back into position by the spring c^2 after the end piece has slipped off from its end. The forward movement of the end piece operates this lever b^2 , so as to cause it to strike the alarm once as the end piece moves past it, and then as the spring d^2 , which is attached to the lever x , draws the lever x back into position, the end piece again moves the lever b^2 as the end piece moves back into position, and thus causes the alarm to sound a second time.

By means of the construction above described, it will be seen that, whether the pull is exerted upon the door-pull or the knob is turned, the alarm is caused to strike twice. It will be seen that both the door-pull and the door knob are attached to the same alarm, and that each one will cause the alarm to strike twice each time either one or the other is moved.

Having thus described my invention, I claim—

1. The combination of the shank of the door-knob with the lever f , the chains connected to its ends, the triangular lever, the connecting rod or chain, the lever x and pivoted end piece, the lever b^2 , suitable springs connected to the levers x and b^2 for returning them to position, and the alarm, substantially as shown.

2. The combination of the door-pull, the connecting rod or wire, the lever g , having the projection h , the lever x , provided with the pivoted end piece, the lever b^2 , suitable springs for returning the levers to position, and the alarm, substantially as shown.

In testimony that I claim the foregoing I have hereunto set my hand this 17th day of March, 1883.

BERNARD FAY.
